CLAIM

The ornamental design for a platform for a tablet dispenser package insert, as shown and described.

DESCRIPTION

FIG. 1 is a perspective view of a platform for a tablet dispenser package insert as seen from top, front and left side showing our new design;

FIG. 2 is a top plan view thereof;

FIG. 3 is a bottom plan view thereof;

FIG. 4 is a front elevational view thereof;

FIG. 5 is a left side elevational view thereof, the right side

elevational view being a mirror image thereof; and,

FIG. 6 is a rear elevational view thereof.
